UNITED STATES PATENT OFFICE.

JOHN A. REED, OF MONON, INDIANA.

DOOR-CHECK.

No. 857,486.

Specification of Letters Patent. Patented June 18, 1907.

Application filed October 29, 1906. Serial No. 341,143.

To all whom it may concern:

Be it known that I, JOHN A. REED, a citizen of the United States, residing at Monon, in the county of White and State of Indiana, have invented certain new and useful Improvements in Door-Checks; and I do declare the following to be a full, clear, and exact description of the invention, such as will enable others skilled in the art to which it appertains to make and use the same.

This invention relates to door checks.

The object of the invention is to provide a door check for supporting a door and locking said door against accidental release.

In the accompanying drawings, in which like reference characters indicate corresponding parts,—Figure 1 represents a front elevation of a portion of a door and frame, showing this invention applied thereto; Fig. 2 represents an enlarged plan view of the form of check shown in Fig. 1; Fig. 3 represents a perspective view of the slide shown in Fig. 1 with the parts separated and in position readily to be assembled. Fig. 4 represents a front elevation of a portion of a door and frame showing another form of the invention; Fig. 5 represents a perspective view of the form shown in Fig. 4 detached; and Fig. 6 represents a vertical transverse section taken through the slide shown in Figs. 4 and 5. Fig. 7 represents a longitudinal vertical section thereof.

In the form illustrated in Figs. 1, 2 and 3, the invention is shown applied to a door 21, the guide rod 26 being arranged horizontally with one end bent and secured to the door frame, the bend therein being designed to limit the movement of the slide 27 in one direction and the other end of said rod being bent to limit the movement of said slide in the other direction. A brace bar 25 is pivotally connected at one end to the slide 27 and to the door 21 at its other end by means of a plate 22 having spaced perforated lateral ears 23, and a pin or bolt 24 is passed through said ears and the end of the bar 25. The slide 27 is preferably made in the form of a block 28 with a longitudinal recess 29 to receive the guide rod 26 in which it slides and with recesses, as 30, arranged in its upper face at opposite sides of said longitudinal recess 29. Screw threaded apertures, are formed in the bottom walls of the recesses, as 30, to receive screw threaded ends of bolts 31 and 32. A packing 33 is arranged in said recess 29 below the guide rod 26 and a pack-

ing 34 fits in the recesses 29 and 30 above said guide rod 26. A top bearing plate 35 is shaped to fit in said recesses 29 and 30 over the packing 34 and has apertures 36 and 37 therein which register with the apertures, in the walls of the recesses 30, and through which the screw bolts 31 and 32 pass. Stout spiral springs 38 and 39 are mounted on these bolts between their heads 65 and the plate 35 to give a yielding action to the bearing plate 35.

In the form illustrated in Figs. 4, 5 and 6 a slide rod or guide 40 is offset from and secured to a door by means of attaching plates 41 and 42 having lugs 43 and 44 preferably made integral therewith, the rod 40 being secured or riveted to said lugs. A slide 50 is mounted on the rod 40 and is limited in its movement thereon by the end lugs 43 and 44. The brace bar 45 is pivotally connected at one end to one member of the slide 50 and its outer end is connected to the door frame by means of a plate 46 having spaced ears 47 and 48 between which the bar 45 is arranged 8c and pivoted on a pin or bolt 49. The slide 50 is composed of two members 51 and 60 fastened together by screws, as 52. The bottom member 51 has a recess 53 extending longitudinally thereof with an enlargement 54 intermediately thereof forming a socket. A packing strip 55 is arranged in the bottom of the recess 53 on which the lower face of the rod 40 slides. Another packing strip 56 is disposed over the rod 40 and has a circular 90 center portion to fit in the socket 54. A metal bearing plate in the form of a disk 57 having oppositely extending arms 58 and 59 is disposed in said member 51 over the packing strip 57, the upper faces of said arms being inclined and the lower faces straight. The top member 60 has a round socket 61 therein to register with the socket 54 in the member 51. This socket 61 has a central screw-threaded opening 62 in its top wall 100 into which a set screw 63 is screwed. The walls of this socket 61 gradually converge toward the opening 62. The member 60 has recesses 64 and 65 at opposite sides of the socket with the bottom walls thereof inclined 105 to fit the inclined faces of the arms 58 and 59 of the plate 57. A small washer 66 and a larger washer 67 are disposed in the socket 61 against which the inner end of the screw 63 bears. A coiled spring 68 of stiff wire is 110 disposed in the socket 61 with one end resting on the large washer 67 and its other end on

the plate 57 when the members 51 and 60 are connected. A supplemental spring 69 is disposed within the spring 68 in the embodiment shown to reinforce and strengthen it.

5 It is to be understood that while this check is shown applied to a door, it may be used for any other purpose for which it is adapted.

Having thus described my invention, what 10 I claim as new and desire to secure by Letters-Patent, is:—

1. In a door check the combination of a guide rod rigidly secured at one end to one side of the door, a slide mounted on said rod 15 and comprising a recessed member having a spring pressed bearing plate fitting in said recess over said rod whereby the rod is clamped between said recessed member and said plate and frictionally held thereby, and a brace 20 pivotally connected with said slide and with the door frame.

2. In a door check the combination of a guide rod fixed at one end to one side of the door, a slide mounted on said rod and comprising a recessed member having a spring 25

pressed bearing plate fitting in said recess over said rod and engaging said rod, to clamp it between said recessed member and said plate, means for regulating the tension of said spring, and a brace pivotally connected 30 with said slide and with the door frame.

3. In a door check the combination of a guide rod mounted on and spaced from one side of the door, a slide mounted on said rod and comprising a recessed member having packing disposed therein on opposite sides of said rod, a plate arranged over said packing, a top member having a socket, a spring disposed in said socket and bearing on said plate, means for regulating the tension of 35 said spring, and a brace pivotally connected 40 with said slide and with the door frame.

In testimony whereof I have hereunto set my hand in presence of two subscribing witnesses.

JOHN A. REED.
